UNITED STATES PATENT OFFICE

2,266,594

MEANS FOR TRANSMITTING POWER

George E. Ertel, Monroeville, Ind.

Application March 26, 1941, Serial No. 385,363

2 Claims. (Cl. 74—27)

This invention aims to provide novel means for changing rotation to straight line reciproca-
tion in a machine. Centrifugal weights are em-
ployed for imparting straight line reciproca-
tion to a slide, and the invention contemplates
such a disposition of the weights that the tend-
ency of the weights to move the slide trans-
versely of its direction of straight line travel will
be minimized.

It is within the province of the disclosure to
improve generally and to enhance the utility
of devices of that type to which the present in-
vention appertains.

With the above and other objects in view, which
will appear as the description proceeds, the in-
vention resides in the combination and arrange-
ment of parts and in the details of construction
hereinafter described and claimed, it being un-
derstood that changes in the precise embodiment
of the invention herein disclosed, may be made
within the scope of what is claimed, without de-
parting from the spirit of the invention.

In the accompanying drawings:

Fig. 1 shows, in side elevation, a machine
constructed in accordance with the invention,
parts being in section;

Fig. 2 is a top plan;

Fig. 3 is a transverse section.

The invention contemplates the use of a
support S, which may include a base frame 1
carrying a table 2. Pairs of posts 3 are erected
on the table 2, the posts of the pairs being con-
nected by tie bars 4. The posts have horizontal
guide bores 5, which preferably are circular in
cross section. The upper ends of the posts 3
are provided with oil cups 6, and oil ducts 7
lead downwardly from the oil cups, to the bores
5, a means thus being provided for lubricating
a slide (hereinafter described), which is mount-
ed for reciprocation in the bores 5. Packings
8 are disposed on opposite sides of the posts 3,
and are held in place by retaining plates 9,
connected by securing elements 10.

The numeral 11 designates a slide, including
parallel rods 12, preferably of circular cross sec-
tion, the rods being mounted for reciprocation
in the guide bores 5, in the packings 8, and in
the retaining plates 9. At one end, the rods 12
of the slide 11 are connected by a transverse
yoke 14, carrying means 15 whereby the slide
may be connected to any instrumentality which
is to be driven.

Parallel beams 16, which may be channels, are
superposed on the rods 12, and are connected
thereto by securing elements 17. Spacers 18

are disposed between the beams 16. Securing
members 19, such as bolts, pass through the
beams 16 and the spacers 18 and bind the beams
against the ends of the spacers, thereby afford-
ing a rigid structure.

To one of the beams 16 is secured a depending
bracket 20. The inner ends of links 21 are piv-
otally mounted on the bracket 20. The outer
ends of the links 21 are connected to pull springs
22, the outer ends of the pull springs being at-
tached to the posts 3.

Anti-friction bearings 23 are secured to the
outer sides of the beams 16 of the slide 11, and
parallel shafts 24 are journaled for rotation in
the bearings. The shafts 24 carry intermeshing
gear wheels 25 of the same size, the gear wheels
being located between the beams 16.

Radius arms 27 are secured to the shafts 24,
between the beams 16. Counterweights 28 of
equal mass are supplied and are grooved trans-
versely, as shown at 29, to receive the arms 27.
Securing elements 30 connect the weights 28
detachably to the arms 27.

On the outer ends of the shafts 24, cone pul-
leys 31 are secured. The cone pulleys 31 co-
operate with belts 32, engaging the cone pulleys
33 on the shafts of motors 35, for instance elec-
tric motors, supported from the base 1, as shown
at 36, and located below the slide 11.

When rotation is imparted to the shafts 24,
by means of the cone pulleys 31, the belts 32,
the cone pulleys 33 and the motors 35, the
weights 28 will impart reciprocating movement
to the slide 11, the rods 12 of the slide recip-
rocating in the guide bores 5 of the posts 3,
and straight line reciprocation being imparted
to any member which is to be driven, by way
of the yoke 14.

The extent of travel of the slide 11, horizon-
tally, may be altered by substituting for the
weights 28, other weights of different mass.
The springs 22 and associated parts constitute
combined shock-absorbing and return members.
The springs 22 and associated parts may be
omitted if desired.

It is understood that the motor 35 may be
duplicated, but a single motor may be used.
Two motors produce a power transmitting ma-
chine which operates somewhat more smoothly
than is the case when one motor is used.

The arms 27 are so located circumferentially
of the shafts 24 that the weights 28 move si-
multaneously toward one end of the slide 11,
and toward the line of reciprocation of the slide
11, and both weights cooperate in the recipro-

cation of the slide. It will be noted, referring to Fig. 1, that when one of the weights 28 is on one side of the line of reciprocation of the slide 11, the other weight is on the opposite side of the line of reciprocation. The weights 28, therefore, tend to neutralize forces tending to move the slide transversely of its line of reciprocation, and the friction of the slide rods 12 in the posts 3 is reduced accordingly.

The device forming the subject matter of this application is simple in operation but will be found thoroughly effective for the ends in view, namely transforming rotary movement into straight line reciprocation, and transmitting the straight line reciprocation to a part to be driven.

Having thus described the invention, what is claimed is:

1. In a machine for changing rotation into straight line reciprocation, a support, a slide, means for mounting the slides for straight line reciprocation on the support, parallel shafts journaled on the slide, intermeshing spur gears of the same diameter secured to the shafts, weights of like mass mounted to move in like

orbits with the shafts, the weights being so disposed, 180 degrees apart, circumferentially of the shafts, that they move simultaneously toward one end of the slide and toward the line of reciprocation of the slide, and then move to positions on opposite sides of the line of reciprocation of the slide, and means for rotating one shaft, thereby to minimize vertical components in the movements of the slide.

2. In a machine for changing rotation into straight line reciprocation, a support having spaced guides, a slide comprising parallel rods, having their opposite end portions mounted to reciprocate in the guides, beams disposed above the rods, to reinforce them against bending, and connections joining the beams; parallel shafts journaled on the beams, intermeshing spur gears of like diameter secured to the shafts, radius arms carried by the shafts, weights of like mass mounted on the arms at equal distances from the centers of rotation of the respective shafts, and means for rotating one shaft.

GEORGE E. ERTEL.
